FILTER-UNIT FORMING MACHINE

George A. Arnold, Chatham, N. J., assignor to
Motor Improvements, Inc., Newark, N. J., a cor-
poration of Delaware

Application July 18, 1939, Serial No. 285,080

22 Claims. (Cl. 242—1)

This invention relates to filter-unit forming machines and more especially to a machine for spirally winding metal ribbon into a disk having filtering interstices provided by transverse ribs or spacers formed at regular intervals on one face of the ribbon. The ribbon is so narrow and thin as to be incapable of self-support and must be guided and supported during the operation of spirally winding it into disk form. A typical ribbon is .07 inch wide, .010 inch thick and the risers or spacers are .0015 inch in height.

An object of this invention is a simple and inexpensive machine which will quickly and efficiently wind the ribbon tightly into spiral form and provide support for the ribbon as it is wound into spiral form.

Other objects, novel features and advantages of this invention will become apparent from the following specification and accompanying drawings, wherein:

Fig. 1 is a front elevation of a machine embodying the invention;

Fig. 2 is an end elevation partially broken away of such machine;

Fig. 3 is a section substantially on the line 3—3 of Fig. 1;

Fig. 4 is a side elevation partially broken away of a partially formed filter produced by the machine;

Fig. 5 is a section on the line 5—5 of Fig. 4;

Fig. 6 is a side elevation similar to Fig. 4 of a complete filter, and

Fig. 7 is a section on the line 7—7 of Fig. 6.

Figs. 4 to 7 inclusive illustrate one embodiment of a filter equipped with a pair of filtering disks each comprising a spirally wound ribbon having transverse ribs providing filtering interstices. In this embodiment, a circular frame 10 has a hub 11 and a rim 12 of equal width with spokes 13 of the same width as the hub and rim extending therebetween.

The hub is provided with peripheral apertures 14 between spokes 13 and between the hub and the rim the spokes are connected by circular bars 15 of less width than the spokes. Also, additional bars 16 extend radially from the inner circular bar 15 to the rim 12. A filtering disk 17 is arranged on each face of the frame 10 and is suitably attached thereto. In Figs. 4 and 5, only one filtering disk 17 has been assembled with the frame 10 while in Figs. 6 and 7, filtering disks 17 have been assembled on both sides of the frame 10. Rings 18 are riveted to opposite ends of the hub 11 and constitute shoul-

ders supporting the innermost turn of the spiral forming the disk 17. As shown in Figs. 4 and 5, rods 19 fastened at opposite ends to the ring 18 and rim 12 by bolts 20 rest against the outer face of the disk 17 to maintain the latter against the ribs 13. After filtering disks have been applied to both sides of the frame 10, both disks are held in place by rods 19, the outer ends of which are attached to the rim 12 by bolts 20 while the inner ends are held in place by bolts 10 21 fastened through collars 22 and taking the place of the inner set of bolts 20 shown in Fig. 5. The collars 22 provide means for mounting the frame on a pipe having apertures communicating with the apertures 14 for the purpose of 15 conducting away filtered liquid, the liquid to be filtered having been supplied to the exterior surface of the disks 19 and having passed through the interstices therein.

Referring now to Figs. 1, 2 and 3, a frame 25 supports a rotating shaft 26. On the shaft 26 is a pulley 27 rotatable with respect to the shaft 26 and having a clutch plate 28 in operative relation to a clutch plate 29 carried by the shaft 26. A spring 30 is arranged between the pulley 27 and a collar 31 supported at the end of a rod 32 extending from the shaft 26. This arrangement constitutes a friction drive for the shaft 26, the pulley being provided with a belt 33 operated at a constant speed by means not shown.

A plate or disk 34 is carried by the shaft 26 and is provided with a hub 35 for receiving the hub 11 of a frame 10, the frame being fastened to the plate by means, not shown. An arm 36 is pivoted to the upper end of a post 37, the outer end of the arm 36 being arranged at right angles to the major portion thereof. The arm 36 is provided with a head into which is threaded a bushing 36a and held in place by a lock nut 36b. A rod 38 is slidably mounted in the bushing 36a and is provided at one end with a nut and washer combination 39 and at the other end is provided with an enlarged head 40 between which and the end of the bushing 36a is provided a coil spring 41. A roller 42 is mounted on the head 40 by means of ball bearings 43. The axis of the roller 42 is parallel to the axis of the shaft 26 and the spring 41 tends to project 50 the roller toward the disk 34. The roller 42 is cut away to provide a cylindrical surface 44 of slightly less width than the ribbon to be wound into spiral form, thus providing a shoulder 45 to engage the edge of said ribbon.

A carriage 46 is supported by a rod 47 slideable in the frame 25 and coaxial with the shaft 26. A guide rod 48 holds the carriage 46 against rotation. A plurality of freely rotatable conical rollers are journaled on shafts supported at their inner ends by the carriage 46 with the axes of said rollers lying in the surface of a cone coaxial with said shaft 26 and with each roller axis being coplanar with said shaft axis. The effective apex of each roller lies in the rotational axis of the plate 34 and the angularity of each roller axis relative to the plate axis is such that the spacing between the roller and plate is uniform throughout the entire length of the roller. The carriage 46 is movable toward and away from the plate 34 and in the rod 47 are provided notches 50 and 51 into which the screws 52 and 53 are adapted to be seated to fix the spacing of the rollers 49 with respect to the plate 34.

Feeding means 54 are provided for supplying ribbon R of the desired size and properly ribbed at a uniform rate of speed. Between the feeding means 54 and the plate 34 are provided suitable guiding means 55 and tensioning means 56.

In the operation of the machine above described, a frame 10 is arranged on the plate 34 with one face in contact with said plate and with the frame hub 11 surrounding the plate hub 35. The end of the ribbon R supplied from the feeding means 54 is attached to the outer surface of the exposed ring 18 after which the arm 36 and the rod 38 are adjusted to bring the surface 44 of the roller 42 into contact with the top surface of the ribbon R and the shoulder 45 into engagement with the edge of such ribbon. A weight 57 on the arm 36 is so adjusted as to cause the roller 42 to exert proper pressure on the ribbon. While the ribbon is being attached to the ring 18 and the roller 42 is being positioned, the rollers 49 are spaced away from the plate as far as possible, but after the ribbon has been attached and the roller 42 has been properly placed, the rollers 49 are moved toward the plate 34 to bring them into proper position to engage the edge of the ribbon R as it is wound up, the screw 52 being inserted into the notch 50 to hold the carriage in proper position. The feeding means 54 and the shaft 26 are now set in rotation and the operation thereof is continued until the proper size disk of spirally wound ribbon has been formed on the face of the frame 10. Slippage of the clutch plates 28 and 29 permits variation in the rotational speed of the shaft 26 to maintain the peripheral speed of the disk at the same linear speed as the rate of feed of the ribbon by the feeding means 54.

The roller 42 presses the ribbon into contact with the frame 10 as the ribbon is being wound up and insures even delivery of the ribbon to the spiral. Also, the roller 42 applies the proper pressure to insure tight winding of the ribbon on the spiral. The shape, size and arrangement of the rollers 49 is such that there is only rolling contact between them and the disk at all times, these rollers serving to hold the ribbon in place as the spiral builds up.

After a disk of proper size has been obtained, the operation of the apparatus is discontinued, the ribbon R is severed and its end is soldered to the frame or to the next inner turn of the ribbon. A few rods 19 are then assembled with the frame and disk as shown in Fig. 4, after which the assembly is removed from the plate

and then remounted on the plate in reverse position, the rods 19 being received in grooves 58 provided in the face of the plate 34. Operation of the machine is then repeated for the purpose of producing the second disk 17, the operation being the same except that the rollers 49 are spaced apart from the plate 34 an additional distance equal to the width of the ribbon, the screw 53 now being received in the notch 51. After the completion of the second disk 17, the end of the ribbon is fixed as previously described and rods 19 are arranged over the face of the second disk in the same manner as before. The completed filter is now removed from the machine and the inner bolts 20 are removed from the rings 18, after which the hub members 22 are inserted in place and attached by means of the bolts 21. Also, a full set of rods 19 is assembled with the disks by means of the bolts 20 and 21.

It is of course understood that various modifications may be made in the structure above described, without in any way departing from the spirit of the invention defined in the appended claims.

I claim:

1. A machine for winding transversely ribbed metal ribbon into a disk form filtering unit comprising a winding hub, driving means therefor, a backing member rotatable with said hub, a roller between which and said hub said ribbon is wound on to said hub, means supporting said roller both for movement toward and away from said hub and for movement toward and away from said backing member, said supporting means having provision for urging said roller toward said hub and said member, said roller having a cylindrical portion of less width than said ribbon engaging one face thereof and an annular shoulder at the end of said cylindrical portion engaging the edge of said ribbon, and conical rollers having their axes lying in the surface of a cone coaxial with said hub and their surfaces in spaced relation to said backing member for engagement with the edge of ribbon wound on said hub.

2. A machine for winding transversely ribbed metal ribbon into a disk form filtering unit comprising a winding hub, driving means therefor, a backing member rotatable with said hub, a roller between which and said hub said ribbon is wound on to said hub, means supporting said roller both for movement toward and away from said hub and for movement toward and away from said backing member, said supporting means having provision for urging said roller toward said hub and said member, said roller having a cylindrical portion of less width than said ribbon engaging one face thereof and an annular shoulder at the end of said cylindrical portion engaging the edge of said ribbon, conical rollers having their axes lying in the surface of a cone coaxial with said hub and their surfaces in spaced relation to said backing member for engagement with the edge of ribbon wound on said hub, and a carrier for said rollers movable axially of said hub.

3. A machine for winding transversely ribbed metal ribbon into a disk form filtering unit comprising a winding hub, driving means therefor, a backing member rotatable with said hub, an arm pivotally supported on an axis parallel to said hub axis, a roller supported by said arm for movement toward and away from said backing member and being gravitationally urged to-

ward said hub, and resilient means urging said roller toward said backing member, said roller having a cylindrical portion of less width than the ribbon engaging one face thereof and an annular shoulder at the end of said cylindrical portion engaging the edge of said ribbon.

4. A machine for winding transversely ribbed metal ribbon into a disk form filtering unit comprising a winding hub, driving means therefor, 10 a backing member rotatable with said hub, an arm pivotally supported on an axis parallel to said hub axis, a roller supported by said arm for movement toward and away from said backing member and being gravitationally urged toward said hub, resilient means urging said roller toward said backing member, said roller having a cylindrical portion of less width than the ribbon engaging one face thereof, an annular shoulder at the end of said cylindrical portion engaging the edge of said ribbon, and conical rollers having their axes lying in the surface of a cone coaxial with said hub and their surfaces in spaced relation to said backing member for engagement with the edge of ribbon wound on said hub.

15 5. A machine according to claim 4 characterized by a carrier for said rollers movable axially of said hub.

6. A machine for winding transversely ribbed metal ribbon into a disk form filtering unit comprising a winding hub, a backing member rotatable with said hub, a roller between which and said hub said ribbon is wound on to said hub, means supporting said roller both for movement 20 toward and away from said hub and for movement toward and away from said backing member, said supporting means having provision for urging said roller toward said hub and said member, said roller having a cylindrical portion of less width than said ribbon engaging one face thereof and an annular shoulder at the end of said cylindrical portion engaging the edge of said ribbon, means for supplying ribbon to said hub at constant speed, and driving means for said hub.

40 7. A machine for winding transversely ribbed metal ribbon into a disk form filtering unit comprising a winding hub, a backing member rotatable with said hub, an arm pivotally supported on an axis parallel to the hub axis, a roller supported by said arm for movement toward and away from said backing member and being gravitationally urged toward said hub, said roller having a cylindrical portion of less width than said ribbon engaging one face thereof and a circumferential flange at one end of said cylindrical portion for engagement with one edge of said ribbon, resilient means urging said roller toward said backing member, means for supplying ribbon to said hub at constant speed, and driving means for said hub.

45 8. A machine according to claim 7 characterized by conical rollers having their axes lying in the surface of a cone coaxial with the hub and their surfaces in spaced relation to said backing member for engagement with the edge of ribbon wound on said hub.

9. A machine according to claim 7 characterized by conical rollers having their axes lying 50 in the surface of a cone coaxial with the hub and their surfaces in spaced relation to said backing member for engagement with the edge of ribbon wound on said hub, and a carrier for said rollers movable axially of said hub.

75 10. A machine for winding transversely ribbed

metal ribbon into a disk form filtering unit comprising a winding hub, driving means therefor, a backing member rotatable with said hub, a roller yieldably urged toward said winding hub radially thereof and between which and said hub said ribbon is wound on to said hub, said roller having a cylindrical portion of less width than said ribbon engaging one face thereof and an annular shoulder at the end of said cylindrical portion engaging the edge of said ribbon, and conical rollers having their axes lying in the surface of a cone coaxial with said hub and their surfaces in spaced relation to said backing member for engagement with the edge of ribbon wound on said hub.

15 11. A machine for winding transversely ribbed metal ribbon into a disk form filtering unit comprising a winding hub, driving means therefor, a backing member rotatable with said hub, a roller yieldably urged toward said winding hub radially thereof and between which and said hub said ribbon is wound on to said hub, said roller having a cylindrical portion of less width than said ribbon engaging one face thereof and an annular shoulder at the end of said cylindrical portion engaging the edge of said ribbon, conical rollers having their axes lying in the surface of a cone coaxial with said hub and their surfaces in spaced relation to said backing member for engagement with the edge of ribbon wound on said hub, and a carrier for said rollers movable axially of said hub.

20 12. A machine for winding transversely ribbed metal ribbon into a disk form filtering unit comprising a winding hub, driving means therefor, a 25 backing member rotatable with said hub, an arm pivotally supported on an axis parallel to said hub axis, and a roller supported by said arm and being gravitationally urged toward said hub, said roller having a cylindrical portion of less width than the ribbon engaging one face thereof and an annular shoulder at the end of said cylindrical portion engaging the edge of said ribbon wound on said hub, and a carrier for said rollers movable axially of said hub.

30 13. A machine for winding transversely ribbed metal ribbon into a disk form filtering unit comprising a winding hub, driving means therefor, a 35 backing member rotatable with said hub, an arm pivotally supported on an axis parallel to said hub axis, a roller supported by said arm and being gravitationally urged toward said hub, said roller having a cylindrical portion of less width than the ribbon engaging one face thereof, an annular shoulder at the end of said cylindrical portion engaging the edge of said ribbon, and conical rollers having their axes lying in the surface of a cone coaxial with said hub and their surfaces in spaced relation to said backing member for engagement with the edge of ribbon wound on said hub.

40 14. A machine according to claim 13 characterized by a carrier for said rollers movable axially of said hub.

45 15. A machine for winding transversely ribbed metal ribbon into a disk form filtering unit comprising a winding hub, a backing member rotatable with said hub, a roller between which and said hub said ribbon is wound on to said hub, means supporting said roller for movement toward and away from said hub and having provision for urging said roller toward said hub, said roller having a cylindrical portion of less width than said ribbon engaging one face thereof and an annular shoulder at the end of said cylindrical portion engaging the edge of said ribbon wound on said hub, and a carrier for said rollers movable axially of said hub.

ribbon, means for supplying ribbon to said hub at constant speed, and driving means for said hub.

16. A machine for winding transversely ribbed metal ribbon into a disk form filtering unit comprising a winding hub, a backing member rotatable with said hub, an arm pivotally supported on an axis parallel to the hub axis, a roller supported by said arm for movement toward and away from said backing member and being gravitationally urged toward said hub, means for supplying ribbon to said hub at constant speed, conical rollers having their axes lying in the surface of a cone coaxial with said hub and their surfaces in spaced relation to said backing member for engagement with the edge of ribbon wound on said hub, and driving means for said hub.

17. A machine according to claim 16 characterized by a carrier for said rollers movable axially of said hub.

18. A machine for winding transversely ribbed metal ribbon into a disk form filtering unit comprising a winding hub, driving means therefor, a backing member rotatable with said hub, and a roller yieldably urged toward said winding hub radially thereof and between which and said hub said ribbon is wound on to said hub, said roller having a cylindrical portion of less width than said ribbon engaging one face thereof and an annular shoulder at the end of said cylindrical portion engaging the edge of said ribbon.

19. A machine according to claim 18 characterized by conical rollers having their axes lying in the surface of a cone coaxial with said

hub and their surfaces in spaced relation to said backing member for engagement with the edge of ribbon wound on said hub.

20. A machine for winding transversely ribbed metal ribbon into a disk form filtering unit comprising a winding hub, driving means therefor, a roller yieldably urged toward said winding hub radially thereof and between which and said hub said ribbon is wound on said hub, said roller having a cylindrical portion of less width than said ribbon engaging one face thereof and a circumferential flange at one end of said cylindrical portion for engagement with one edge of said ribbon and spaced guide members for engagement with opposite edges of the ribbon advancing to said hub.

21. A machine for winding transversely ribbed metal ribbon into a disk-form filtering unit comprising a winding hub, driving means therefor, a backing member rotatable with said hub, and a roller yieldably urged toward said winding hub radially thereof and between which and said hub said ribbon is wound on said hub, said roller having a cylindrical portion of less width than said ribbon engaging one face thereof and a circumferential flange at one end of said cylindrical portion for engagement with one edge of said ribbon.

22. A machine according to claim 21 characterized by conical rollers with their axes lying in the surface of a cone coaxial with said hub and their surfaces in spaced relation to said backing member for engagement with the edge of ribbon wound on said hub.

GEORGE A. ARNOLD. 35
